UNITED STATES PATENT OFFICE.

LEONCE GARNIER, OF SAN SEBASTIAN, SPAIN.

FUEL-FEEDING APPARATUS FOR EXPLOSION-ENGINES.

1,315,625.

Specification of Letters Patent.

Patented Sept. 9, 1919.

Application filed November 13, 1918. Serial No. 262,305.

To all whom it may concern:

Be it known that I, LEONCE GARNIER, citizen of the Republic of France, residing at 9 Calle Miracruz, San Sebastian, in the 5 Kingdom of Spain, have invented new and useful Improvements in Fuel-Feeding Apparatus for Explosion-Engines, of which the following is a specification.

This invention relates to a fuel feeding 10 apparatus for explosion engines of the known type in which the depression produced in the admission pipe of the motor is used to elevate the fuel from a main tank to a fuel feeding apparatus or auxiliary 15 feeding tank, from which the fuel is directed to the constant level tank of the engine.

A characteristic feature of the fuel feeding tank constructed in accordance with the present invention is the provision of a float 20 carrying a tube or tubular valve which acts as an air distributer so as to control the supply of fuel to the said auxiliary or fuel feeding tank.

In the annexed drawing: 25 Figure 1 is a vertical section of a fuel feeding apparatus constructed in accordance with the invention.

Fig. 2 is a side elevation of a modified construction, the outer casing being partly 30 broken away.

Fig. 3 is a diagrammatical view of the fuel feeding apparatus in combination with fuel tanks and an explosion engine.

The apparatus comprises an outer casing 35 *r* divided into an upper or receiving chamber *R* and a lower or delivery chamber *R'* which may be put in communication by means of a valve *H*. In the upper chamber *R*, is arranged a float *F* which is adapted to 40 vertically slide along the lower part of an air distributing tube *T*, the vertical displacement of the float on the tube being limited at the top by a shoulder *T'* of the tube *T* and at the bottom by a pin *X* carried by said tube. The tube *T* may itself 45 slide with a slight friction in a sleeve or neck *S* carried by the lid of the outer casing. The upper end of the tube *T* is closed by a plug provided with small openings and carrying a valve *P*, the head of which may seat 50 against an opening *A* provided in a nipple which is connected by a pipe *6* to the admission pipe *2* of the engine. The tube *T* is

also provided with lateral openings *O'* which are adapted to register with openings *O* provided in the outer sleeve or neck *S*. Said neck *S* is provided with a cross pin *N* which extends through a vertical slot *M* of the tube *T* whereby said tube is guided in its vertical movement and prevented from 60 turning so that the openings *O'* can properly register with the openings *O*. The cross pin *N* serves also to limit the downward movement of the tube *T* within the sleeve *S*. Holes *D* are provided to put the 65 inside of tube *T* in communication with the upper chamber *R*.

The outer casing is provided at its bottom with a nipple *V* which is in communication, by a pipe *5* with the constant level 70 tank *3* of the carbureter *4* of the engine. A hole *L* provided in the upper part of the outer casing serves to maintain the lower chamber *R'* in constant communication with the atmosphere. The upper chamber *R* is 75 in constant communication with the main supply tank *7* by means of a pipe *B*, a glass sleeve *B'* being provided to enable the proper working of the apparatus to be easily checked. *B*² is a filtering wire screen. 80

The operation of the described apparatus is as follows: In the operation of the motor, the vacuum produced in the admission pipe of the same is transmitted into the upper compartment *R* through the opening *A*, the 85 small openings in the plug carried by the upper end of the tube *T*, the interior space of said tube and the openings *D* which extend from the inside of the tube *T* to the chamber *R*. Said chamber *R* being supposed to be empty and the float being therefore in its lower position as shown in the drawing, the fuel is sucked in and comes to the chamber *R* through the pipe *B* and glass tube *B'*. The float *F* is thus raised and 90 slides first along the tube *T* until its upper face comes into contact with the shoulder *T'*, the tube *T* being then raised together with the float and reaching its uppermost position in which the valve *P* closes the 95 opening *A*. The action of the depression in the admission pipe of the motor is thus stopped and in that position of the parts, the openings *O'* in tube *T* register with the openings *O* in sleeve *S*, so that the atmospheric pressure is admitted into the chamber *R*. 100

105

ber R, above the fuel contained in the same, through the openings O, O' and D. The fuel in chamber R is thus permitted to flow past the valve H into the lower compartment 5 R' from which the fuel passes to the constant level tank of the carbureter through the nipple V. The fuel level being thus lowered in chamber R, the float F descends first along the tube T and, when the lower 10 face of said float comes into contact with the cross pin X the tube T is itself carried on downwardly so that the suction opening A is again opened and the openings O and O' come out of register. The fuel in the 15 main supply tank is thus drawn again by the engine into the chamber R through the pipe B and the operation above described is repeated.

In practice, as the rate of flow of the fuel through the pipe B to the chamber R is greater than the outflow through the nipple V, the fuel level in the apparatus is subjected to slight variations only.

It will be remarked that the float F might be rigidly secured on the tube T but the dead motion arrangement described above is advantageous in that the operation of the apparatus is smoother, the level of the fuel contained in chamber R being allowed to be raised or lowered during certain periods before the tube T is positively actuated by the float.

The construction shown in Fig. 2 is substantially the same as that of Fig. 1 with the exception that the float F is not mounted on a downward extension of the tube T itself but pivotally connected to a lever K which is itself pivoted at one end upon the lid of the outer casing, the free end of said lever moving between two studs U, U' carried by the lower part of the air distributing tube T.

Having now described my invention what I claim as new and desire to secure by Letters Patent is:

1. A fuel feeding apparatus for explosive engines comprising in combination a main fuel tank, a constant level tank, a delivery chamber, means affording a constant communication between the lower part of said chamber and the constant level tank, means affording a communication between the upper part of said chamber and the atmosphere, a receiving chamber, a valve adapted to set both chambers in communication with each other, means affording a communication between the receiving chamber and the main fuel tank, a tubular neck on the receiving chamber, said tubular neck having lateral openings which open into the atmosphere and being provided with an end wall, a tubular slide valve adapted to move in said neck, means affording a communication between the inside of said slide valve and the receiving chamber, the slide valve

having lateral openings which are adapted to register with the lateral openings in the tubular neck, a suction pipe, a conduit connecting said suction pipe to a port in the end wall of the tubular neck, a flap valve carried at the end of the slide valve and adapted to close said port and a float in the receiving chamber adapted to operate the slide valve in an upward and downward direction. 75

2. A fuel feeding apparatus for explosive engines comprising in combination a main fuel tank, a constant level tank, a delivery chamber, means affording a constant communication between the lower part of said chamber and the constant level tank, means affording a communication between the upper part of said chamber and the atmosphere, a receiving chamber, a valve adapted to set both chambers in communication with each other, means affording a communication between the receiving chamber and the main fuel tank, a tubular neck on the receiving chamber, said tubular neck having lateral openings which open into the atmosphere and being provided with an end wall, a tubular slide valve adapted to move in said neck, means affording a communication between the inside of said slide valve and the receiving chamber, the slide valve having lateral openings which are adapted to register with the lateral openings in the tubular neck, a suction pipe, a conduit connecting said suction pipe to a port in the end wall of the tubular neck, a flap valve carried at the end of the slide valve and adapted to close said port, a downward extension provided on the slide valve, said downward extension being provided with stops, and a float in the receiving chamber, adapted to operate the slide valve and move freely between said stops. 100 105

3. A fuel feeding apparatus for explosive engines comprising in combination a main fuel tank, a constant level tank, a delivery chamber, means affording a constant communication between the lower part of said chamber and the constant level tank, means affording a communication between the upper part of said chamber and the atmosphere, a receiving chamber, a valve adapted to set both chambers in communication with each other, means affording a communication between the receiving chamber and the main fuel tank, a tubular neck on the receiving chamber, said tubular neck having lateral openings which open into the atmosphere and being provided with an end wall, a tubular slide valve adapted to move in said neck, means affording a communication between the inside of said slide valve and the receiving chamber, the slide valve having lateral openings which are adapted to register with the lateral openings in the tubular neck, a suction pipe, a conduit connecting 110
115
120
125
130

said suction pipe to a port in the end wall of the tubular neck, a flap valve carried at the end of the slide valve and adapted to close said port, a downward extension 5 provided on the side valve, said downward extension being provided with stops, a lever having one end extending between said stops,

means for pivotally supporting said lever at the opposite end and a float in the receiving chamber, in engagement with the lever 10 at a point intermediate its length.

In testimony whereof I have signed my name to this specification.

LEONCE GARNIER.
